UNITED STATES PATENT OFFICE.

DWIGHT E. PRIEST, OF WORCESTER, MASSACHUSETTS, ASSIGNOR TO PARKER WIRE
GOODS CO., OF WORCESTER, MASSACHUSETTS, A CORPORATION OF MASSACHUSETTS.

DESIGN FOR A BIRD-CAGE HOOK.

Application filed March 16, 1927. Serial No. 21,151. Term of patent 14 years.

To all whom it may concern:

Be it known that I, DWIGHT E. PRIEST, a citizen of the United States, residing at Worcester, in the county of Worcester and State of Massachusetts, have invented a new, original, and ornamental Design for Bird-Cage Hook, of which the following is a specification, reference being had to the

accompanying drawing, forming part thereof.

The figure is a side elevation of a bird cage hook, showing my new design.

I claim:

The ornamental design for a bird cage hook as shown.

DWIGHT E. PRIEST.
